UNITED STATES PATENT OFFICE.

EDWIN BURHORN, OF HOBOKEN, NEW JERSEY.

COOLING TOWER.

Application filed July 7, 1921. Serial No. 483,111.

To all whom it may concern:

Be it known that I, EDWIN BURHORN, a citizen of the United States, residing at Hoboken, in the county of Hudson and State 5 of New Jersey, have invented certain new and useful Improvements in Cooling Towers, of which the following is a specification, reference being had therein to the accompanying drawing.

10 This invention is a novel cooling tower, that is to say, an apparatus of the class by which natural air currents are brought into contact with the water to be cooled, the latter being caused to pass by gravity through 15 the tower while subjected to the cooling influence. More especially the invention relates to the class of cooling tower in which the descent of the warm water is interrupted and delayed by means of one or more structures or cooling decks arranged at various 20 points in the height of the tower for the purpose of preventing a too rapid passage of the water and failure to sufficiently cool the same.

25 The general object of the present invention is to improve the structure of cooling towers of the kind referred to. A particular object is to provide a cooling tower of greater durability and more free from corrosion. Other objects and advantages of the 30 invention will appear in the hereinafter following description or will be apparent to those skilled in the art.

To the attainment of the above referred 35 to objects and advantages, the present invention consists in the novel combination, arrangements, constructions, devices and other features shown or described herein.

In the accompanying drawings showing 40 one form or embodiment of the invention, Figure 1 is a side elevation of a cooling tower embodying my invention, the same partly broken away and certain parts omitted to more clearly show the structure.

45 Figure 2 is an enlarged side elevation, partly in vertical section, of certain details of Fig. 1;

Figure 3 is a section taken on the line 3—3 of Figs. 1 or 2;

50 Figure 4 is a section taken on the line 4—4 of Fig. 1;

Figure 5 is a side elevation taken at right angles to the elevation of Fig. 1; and

55 Figure 6 is a partial plan view, partly in horizontal section, on the line 6—6 of Fig. 1.

Above a suitable supporting base 9 are the tower uprights or corner posts 10 and these, at the top, are interconnected by the cross braces 11. Along each of the four sides may be a series of louvers 12, although 60 these are mostly omitted from the drawings to give better view of the details. The water falling through the tower, and that delivered from the louvers is received in a collecting pan 14 from which a drain pipe 65 15 conducts the water to the condenser or other apparatus. After the water has been again heated it may be returned to the apparatus by a pipe 16, which carries it to a distributing cross pipe 17 at the top, supported by brackets 18, and having apertures 19 serving as orifices to discharge the water in the form of sprays upon or into the distributing members or troughs of the topmost deck 21 below.

In addition to the topmost deck 21, there may be other decks 22, 23 or 24, spaced suitably apart so that the descending water is caught and distributed by each deck and delayed in its descent so as to insure maximum cooling by contact with natural air currents and by evaporation.

The several cooling decks may be of substantially identical construction, but preferably the distributing members or troughs 80 in each deck are arranged crosswise or at right angles to those of the decks above or beneath.

Referring to the structure of any one of the decks, it will be seen that it is supported 90 by underlying channels or beams 26 constituting part of the framework of the tower, and having upper flanges 27 upon which the deck members directly rest.

The distributors or troughs 28 are shown 95 arranged horizontally in parallel relation in each deck, and slightly spaced apart. Each trough is provided with overflow notches 29 so that the accumulating water will pass out of each trough at designated 100 points in relation to the distributing members of the deck beneath, for example into one of the troughs beneath.

In such cooling towers there has been a long known and decided problem in respect 105 to the deterioration of the louvers and troughs and the expense involved in their frequent replacement. Theoretically sheet iron is the ideal material for these parts because of its strength and cheapness. Cor-

- rosion however takes place, due largely to the peculiar conditions existing in a cooling tower. The inherent action in a cooling tower is to permit natural air currents to
- 5 pass through the tower for evaporating and cooling the water. The combined action of the warm water and air is to oxidize or rust the iron and frequently this corrosion is accentuated, due to the fact that the water
- 10 takes up acids which are frequently present in the air, for example, from smoke stacks in the neighborhood of the cooling tower. Galvanized iron has been tried but its life is short and its replacement frequent.
- 15 Zinc gives a longer life, but is more expensive and even this material deteriorates with considerable rapidity. So pronounced has this evil been that frequently the destructible parts of the tower have been made
- 20 of wood. Besides the warping and other defects of wood it is found that it rots rapidly, so that its life is not substantially better than in the other cases.
- I herein propose to employ a non-corrosive alloy having a large percentage of zinc, but in a different manner from the heretofore attempted use of zinc for the purpose. It is to be understood that the posts, beams and other heavy parts of the tower
- 25 are composed of structural steel or iron as usual. The result of embodying zinc or an alloy for the louvers, troughs, etc. is that a decided electrolytic action sets up. What with the presence of the warm water, frequently acidified, for example, by acids in the air, and the two distinctive metals, the cooling tower becomes a galvanic battery, so that the natural corrosion of metals is very greatly enhanced.
- 30 40 In the present invention I employ a non-corrosive metal or alloy for the troughs and louvers and I connect these up with the frame members of the tower by connections comprising insulating strips or layers so as
- 35 45 to preclude electrical or metallic contact between any two metal parts composed of different metals. By this improvement the life of a cooling tower is multiplied many times and I believe with this invention I am the
- 50 55 first to overcome the long existing liability to deterioration of cooling towers.

Referring in detail to the present structure the louvers 12 and the troughs or distributing members 28 are composed of a non-corrosive alloy. I prefer a metal containing a large percentage of zinc such as the "Matola metal" which I have already successfully used in this invention, which is not subject to rusting or deterioration in ordinary conditions, but which would be subject to electrolysis if that action were permitted.

Between the cross beams or channels 26, of structural steel, and the overlying troughs 28 of zinc alloy are shown insulat-

ing strips 33. These strips, like the other insulating members to be referred to may be composed of hard fiber such as compressed wood pulp, cotton rags or asbestos.

The troughs extend across the cooling tower from side to side and rest upon the fiber strips 33 as aforesaid.

In Fig. 5 the troughs are shown as resting also upon the additional fiber strips 34 located between the troughs and certain additional cross beams 35. In this figure the troughs are shown bolted down to the middle beams 35, the ends of the troughs being free for expansion and contraction. This is considered a valuable subsidiary feature in that the tower is preserved from injury by the effects of expansion and contraction. In Figs. 1 and 4 the troughs are bolted down at their ends by bolts 36 to the upper flanges of the cross beams 26, this being sufficient in some cases, especially when room for expansion is provided as will be clear from Fig. 4. In Fig. 5 there will be no bolts at the ends of the troughs but bolts 37 hold the trough down upon the cross beams 35. In Figs. 1 and 4 the bolts 36 not only hold the troughs in place but hold the insulating strips 33. In Fig. 5 separate bolts 38 are provided to hold the insulating strips upon the cross beams 26.

Each bolt may be provided additionally with a fiber washer 40 beneath the head or nut of the bolt and sleeves 41 preventing the body of the bolt contacting the troughs.

As seen in Figs. 1, 2 and 3 each louver 12, composed of zinc alloy, is supported diagonally upon the opposite corner posts 10. While the louver might be flanged for this purpose I have shown iron angle pieces 43, each having one side riveted or bolted to the frame and the other flange giving support to the louver. Between this flange and the louver is an insulating strip or block 44. The parts are secured together by a bolt 45 which is kept from contact with the louver by a washer 46 as in the case of the troughs. The bolts 36 and 45 are preferably of galvanized iron and are not subject to rapid deterioration.

I have thus disclosed a cooling tower embodying the principles and attaining the advantages of the present invention. The life of the described cooling tower is very much greater than any heretofore known. I claim broad novelty in the general principles and combinations disclosed and also specific novelty in the particular constructions and arrangements by which the principles are carried out. Since many matters of combination, arrangement, construction and design may be variously modified without departing from the principles of the invention it is not intended to limit the invention to such matters except so far as set forth in the appended claims.

What I claim is:

1. A cooling tower having an iron frame, distributing members or water troughs of non-rusting metal secured to said frame, and 5 insulating pieces interposed between said members and frame, said distributing troughs being secured to underneath frame beams by bolt members passing through the trough bottoms, the insulating pieces and 10 the beams.

2. A cooling tower having an iron frame, distributing members or water troughs of non-rusting metal secured to said frame, and insulating pieces interposed between said 15 members and frame, each distributing trough being secured near its middle to the frame, leaving its ends free to contract and expand.

3. A cooling tower having an iron frame, 20 means for distributing the water falling in the tower, a series of louvers of non-rusting metal secured to the frame, each louver being supported at its ends, iron angle pieces attached to the frame in position to support 25 said louvers, insulating pieces between the

angle pieces and louver ends, and means to secure the same rigidly together.

4. A cooling tower comprising an iron frame having uprights, and iron members thereon for supporting a series of superposed water distributing decks, and such decks, each comprising a plurality of distributing members of non-rusting metal, insulating pieces interposed between said distributing members and said iron supporting members, and securing bolts rigidly interconnecting the distributing members, the insulating pieces and the supporting members, a warm water connection to the upper part of the tower, and a receiving vessel at 40 the bottom.

5. A cooling tower as in claim 4 and wherein are series of louvers of non-rusting metal spanning the spaces between frame uprights, and means rigidly connecting said 45 louvers to the frame without metallic contact.

In testimony whereof, I have affixed my signature hereto.

EDWIN BURHORN.
